UNITED STATES PATENT OFFICE.

LEON F. DOUGLASS, OF MENLO PARK, CALIFORNIA.

FLINT LIGHTER.

Application filed November 5, 1925. Serial No. 67,099.

This invention relates to flint lighters of the pocket type embodying means for producing a flame. The invention pertains particularly to the arrangement of the parts necessary for producing a spark and the means for providing materials used therein.

An object of this invention is to provide a satisfactory means for producing a spark whereby a flame may be secured.

Another object of this invention is to provide a pocket size flint lighter having novel and satisfactory means for supplying materials for furnishing a spark and a flame.

In the accompanying drawing constituting a part of this application:

Fig. 1 is a sectional view of the flint lighter comprising my invention;

Fig. 2 is a sectional view of a part of the flint lighter showing the means used in causing the flint to contact with the friction wheel to produce a spark; and

Fig. 3 is a top view of the flint lighter.

Referring to the drawing, the numeral 1 represents a casing, having a bottom 2 and a top 3. Extending from the bottom 2 through the top 3 is tubular member 4, provided on its inside surface with suitable threads within which a flat disc 5 having its edges threaded, may be screwed. The tubular member 4 projects through the top of the casing 1 and is provided at its end with upwardly extending side lugs 6, between which is pivoted a friction wheel 7 on a pivot 8. It will be noted that the friction wheel 7 has part of its circumferential edge roughened, and is mounted for pivotal movement in a plane passing longitudinally through the central part of the casing 1. Located inside the tubular member 4 adjacent the disc 5 is a spiral wire spring 9, the lower end of which rests against disc 5 and the upper end of which presses against a bar 10, of flint or other suitable pyrophoric metal, one end of which bar projects through the end of tubular member 4 and contacts with the roughened segment of the friction wheel 7. Removably located within the tubular member 4 and extending upwardly therein through the bottom 2, is a manipulating rod 11, provided with pronged parts 12 and a flat circular finger piece 13, the rod 11 being normally held in position in the tube 4 by the resiliency of the parts 12 which engage the inner surface of said tube. The pronged parts 12 are adapted to grasp the disc 5, and when the finger piece 13 is turned,

the disc may be screwed upwardly or downwardly inside the tubular member in such a manner as to cause the spring 9 to press more or less firmly against the bar 10. The fingerpiece 13 fits within a suitable groove in the bottom 2 of the casing 1, and by its withdrawal, together with the other parts within the tubular member, permits the bar 10 to be removed or replaced when a new one is needed.

Located adjacent the tubular member 4 is a wick tube 14 which extends through the top 3 and is provided therein with a wick 15, one end of which projects from the top 70 of the tube and the other end of which extends into the casing 1.

In the top 3, and extending into the inside of casing 1 with its upper part projecting above the said top, is tube 16, which is provided at its bottom end with a screw 17 and at its upper end with a pair of separated projecting lugs 18. The tube 16 is provided near its upper part with an interior shoulder 19, and above the shoulder with a central bore of somewhat reduced diameter in which is slidably mounted a pin 20, the upper end of the latter being adapted to be moved beyond the upper end of the tube 16. The lower end of the pin is provided with a head 85 21 which may strike against the shoulder 19 and prevent the pin 20 from moving upwardly too far, as will be explained herein. Located inside the tube 16 below the head 21, is a spiral wire spring 22, one end of 90 which presses against the screw 17 and the other end of which presses against the head 21, thereby tending to force the pin 20 in an upward direction.

Rigidly attached to the friction wheel 7 95 or formed integrally therewith, is an arm 23 provided with a cap portion 24 which constitutes a closing cap for the end of the wick tube 14. The arm 23 moves on the pivot 8 and is adapted to lie between lugs 18 of the tube 16, thereby coming into contact with the projecting end of pin 20. The end of the arm 23 is provided with a latch portion constituted by a hollow ball 25 which has an opening 26 located on its lower side. 100

Located on the top 3 between the tube 16 and an end of the casing, is projection 27 to which is pivoted, as by means of a pin 28, a latch lever 29 having an upwardly projecting catch portion 30 which extends 110 through opening 26 into engagement with the inner surface of ball 25, and a laterally

projecting portion which extends substantially parallel to the top of the casing and is provided at its extremity with a pressed member or finger piece 31. Preferably a 5 suitable spring 32 is interposed between the portion 31 of the lever 29 and the casing in order to normally maintain latch portion 30 in latching engagement with ball 25, whereby arm 23 is held against movement about 10 pivot 8. The opening 26 is of such size that latch portion 30 of lever 29 may pass freely therethrough.

The bottom 2 of the casing 1 is provided with a cap 33 which is adapted to screw into 15 the said bottom and close an opening provided therein for the insertion of gasoline or other fuel used to make the flame at the end of the wick 15.

In operation, the inside of the casing 1 20 may be filled with any absorbent material such as cotton, and gasoline or other suitable fuel is placed inside the casing through the bottom, by the removal of cap 33. By manipulating the finger piece 13, the rod 11 25 through its pronged parts 12, is made to screw the disc 5 upwardly until the bar 10 presses against the friction wheel 7 and causes a spark to be made by the friction of the said wheel rubbing against the said bar. 30 As shown in Fig. 1, arm 23 is normally maintained by the latch means in a horizontal position substantially parallel to the top 3 of casing 1 with the closing cap 24 closing the end of wick tube 14, the said arm 35 pressing against pin 20 and lying between the lugs 18. To light the wick 15, the press member 31 is pressed downwardly by the finger, thereby causing the projecting end 30 of the lever 29 to become disengaged 40 from the hollow ball 25. The spring 22 pressing against the head 21 of the pin 20 causes the said pin to move upwardly and throw the said arm 23 in an upward direction, thereby turning the friction wheel 7 and 45 causing it to produce a spark through its rubbing action against the bar 10. The spark thus caused, ignites the fuel at the end of the wick 15, and the same burns until the arm 23 is placed back in its former position 50 with the closing cap 24 over the end of the wick tube 14.

Having described my invention, what I claim is:

1. In a flint lighter, the combination of a 55 casing having a top and bottom, a tubular member extending through the inside of the casing from the bottom and through the top, a friction wheel movably attached to the end of the tubular member at a point there- 60 on above the top, a bar located in the tubular member and contacting with the friction wheel whereby a spark may be produced by the movement of the friction wheel against the bar, means including a member provid- 65 ed with flexible pronged parts located in

the tubular member for moving the bar upward within the tubular member, a wick located adjacent the friction wheel, and means for partially revolving the friction wheel.

2. In a flint lighter, the combination of a casing, a tubular member extending through said casing, a friction wheel movably located on the tubular member exteriorly of said casing, a pyrophorous body located inside the tubular member and contacting with the friction wheel, means including a disk and a pronged member for moving said disk in either direction located inside the tubular member for moving the said body upward inside the tubular member, a wick located adjacent the friction wheel, an arm carrying a closing cap for covering the wick secured to the friction wheel, and means for moving the said arm and said friction wheel whereby the wick is uncovered and the friction wheel is rotated against the said body to produce a spark.

3. In a flint lighter, the combination of a casing having a top and a bottom, a tubular member extending from a point above the top through the inside of the casing to the bottom, a friction wheel revolvably secured to the end of the tubular member above the top, a pyrophorous body located in the tubular member and contacting with the friction wheel, means located in the tubular member for moving the said body upward, said means including a resilient member, a disk having engagement with said resilient member, and rotatable means having sliding engagement with the disk for moving the latter upwardly or downwardly, a wick tube located adjacent the friction wheel having a wick therein, an arm secured to the friction wheel having a closing cap adapted to cover the end of the wick tube, means located on the top for holding the said arm in a horizontal position above the top and for releasing the same, and means for throwing the said arm in an upward direction when the same is released by the first mentioned means, whereby the wick tube may be uncovered and the friction wheel may be made to rotate to produce a spark.

4. In a flint lighter, the combination of a casing having a top and a bottom, a tubular member extending from the bottom through the inside of the casing to a point above the top, a friction wheel revolvably attached on the tubular member above the top, a pyrophorous body located inside the tubular member and contacting with the friction wheel, means located inside the tubular member for adjusting the pressure of the said body against the friction wheel, a wick tube having a wick therein located on the top adjacent the friction wheel, an arm rigidly secured to the friction wheel having a hollow ball on its end and a closing cap adapted to cover

- the end of the wick tube, means secured to the top for grasping the hollow ball whereby the arm may be held in a horizontal position above the top and for releasing the said ball, means located on the top for throwing the said arm in an upward direction when the first mentioned means is released from the hollow ball, whereby the wick tube may be uncovered and the friction wheel may be rotated against the said body to produce a spark for igniting the said wick.
5. A device of the class described comprising a casing, a tube within said casing, an ignitable body carried by the casing, means including a pyrophoric element mounted in said tube for igniting said body, and means for adjusting the position of the pyrophoric element, said last-named means including a resilient member in said tube, 15 a disk adapted to engage said resilient member, and a bifurcated member for adjusting said disk.
10. A pocket lighter comprising a casing, an ignitable member projecting from said casing, means for igniting said ignitable member including a pivoted arm, means normally preventing movement of said arm, and means for rotating said arm, said last-named means including a sleeve extending through a wall of said casing into engagement with said arm, a plunger in said sleeve, and resilient means for normally maintaining said plunger in engagement with said arm. 70
15. A device of the class described comprising a casing, an ignitable element projecting from said casing, means for igniting said element including a swinging arm having a serrated portion, said arm being pivotally secured to said casing, means including a spring-pressed lever for locking said arm against movement, and means normally housed within the casing and having 75 abutting engagement with the lower face of said arm for swinging the latter through an angle of substantially 180°.
20. A device of the class described comprising a casing, a tube within said casing, an ignitable body carried by the casing, means including a pyrophoric element mounted in said tube for igniting said body, and means for adjusting the position of the pyrophoric element, said last-named means including means in said tube having engagement with said element, and means slidably mounted in said tube for moving said last-named means longitudinally of the tube in both directions. 80
25. A device of the class described comprising a casing, an ignitable member carried thereby, means for igniting said member including a serrated member and a pyrophoric member, and means for adjusting the position of the pyrophoric member, said last-named means including a resilient member having engagement with the pyrophoric member, a disk engaging the resilient member, and a member having a portion extending exteriorly 85
30. of the casing and adapted to engage the disk on the opposite sides thereof.
35. A lighter comprising a casing, an ignitable member carried thereby, means for igniting said member including a serrated member and a pyrophoric member, and means for adjusting the position of the pyrophoric member, said last-named means including a resilient member having engagement with the pyrophoric member, a disk engaging the resilient member, and a member having a portion extending exteriorly 90
40. of the casing and adapted to engage the disk on the opposite sides thereof.
45. A lighter comprising a casing, a tube extending therethrough, a wick carried by the casing and having one end thereof extending outwardly of the casing, means for igniting said wick including a rotatable serrated member and a pyrophoric member, the latter being slidably mounted in said tube, and means for adjusting the engagement of the pyrophoric member with the serrated member, said means including a resilient member in said tube, a rotatable disk adapted to engage said resilient member, and slidable means for rotating said disk. 95
50. A device of the class described comprising a casing, an ignitable member carried thereby, means for igniting said member including a pivoted arm, and means for rotating said arm, said last-named means includ- 100
55. ing a sleeve having a portion extending within the casing, and means including a plunger slidably mounted in said sleeve and adapted to engage said arm.
60. A pocket lighter comprising a casing, an ignitable member projecting from said casing, means for igniting said ignitable member including a pivoted arm, means normally preventing movement of said arm, and means for rotating said arm, said last-named means including a sleeve extending through a wall of said casing into engagement with said arm, a plunger in said sleeve, and resilient means for normally maintaining said plunger in engagement with said arm. 105
65. A device of the class described comprising a casing, an ignitable element projecting from said casing, means for igniting said element including a pyrophoric member and a swinging member, a sleeve removably secured to said casing and having a portion projecting exteriorly of the casing, and resilient means in said sleeve for swinging said arm. 110
70. A device of the class described comprising a casing, an ignitable element carried thereby, means including a movable arm for igniting said element, said arm being provided with a hollow portion having an opening therein, and means mounted on the casing having a portion extending through said opening for normally preventing movement of said arm. 115
75. A device of the class described comprising a casing, an ignitable element carried thereby, means including a movable arm for igniting said element, said arm being provided with a hollow portion having an opening therein, a lever pivotally secured to the casing and having a portion extending through said opening, and resilient means for normally maintaining said lever portion in engagement with the hollow portion of said arm. 120
80. A device of the class described comprising a casing, a plurality of tubes pro- 125
85. 90. 95. 100. 105. 110. 115. 120. 125. 130.

jecting from the top of said casing, means including a pyrophoric member in one of said tubes, means including an arm having a serrated portion in engagement with said member, means for pivotally securing said arm to said tube containing the pyrophoric member, means including a plunger and a resilient member in one of said tubes, said plunger normally having engagement with 5 said arm, and an ignitable member projecting from one of said tubes intermediate said plunger and said pyrophoric member.

17. A device of the class described comprising a casing, a tube extending through 10 said casing, the lower end of said tube being flush with the bottom of the casing and the upper end of the tube projecting beyond the top of the casing, means including a pyrophoric member and a slidably 15 mounted and manually adjustable member in said tube, an arm pivoted to said tube, said arm including a serrated portion, a cap portion, and a latch portion, said serrated portion having engagement with the 20 pyrophoric member, ignitable means adapted to project through the casing into said cap portion, means carried by the casing and having abutting engagement with the arm intermediate said cap portion and said serrated portion for rotating said arm, and 25 means including a pivoted lever mounted exteriorly of the casing and adapted to coat with said latch portion for normally preventing rotation of the arm.

18. In a pocket lighter, the combination 35 with a casing of a pyrophoric element carried by the casing, a serrated member pivotally secured to the casing and adapted to coat with the pyrophoric member for producing a spark, an ignitable member carried 40 by the casing and adapted to be ignited by said spark, means for rotating the serrated member, and means for adjusting the engagement of the pyrophoric member with the serrated member, said last-named means 45 including a resilient member having engagement with the pyrophoric element, a threaded disk having engagement with the casing and said resilient member, and a knurled bifurcated member for rotating said 50 disk in either direction.

19. A device of the class described comprising a casing adapted to receive an ignitable liquid, a wick carried by the casing and extending into said liquid, means for igniting the wick including a movable arm having a serrated portion, a wick cap portion and a latch portion, means normally preventing rotation of said arm including a member pivoted to the outer surface of the casing 55 and adapted to engage said latch portion, and means extending through the casing intermediate the ends of said arm for swinging the arm as the same is released by said pivoted member whereby the wick is ignited. 60 65
